LEVI DEDERICK, OF NEW YORK, N. Y.

Letters Patent No. 90,431, dated May 25, 1869.

IMPROVED HAY AND COTTON-PRESS.

The Schedule referred to in these Letters Patent and making part of the same.

To all whom it may concern:

Be it known that I, LEVI DEDERICK, of the city, county, and State of New York, have invented a new and useful Improvement in Hay and Cotton-Press; and I do hereby declare that the following is a full, clear, and exact description thereof, which will enable others skilled in the art to make and use the same, reference being had to the accompanying drawings, forming part of this specification.

The figure is a side view of my improved press, partly in section, to show the construction.

My invention has for its object to improve the construction of hay, cotton, and other baling-presses, so as to make them more convenient and effective in operation, the follower being made to move up and down with a uniform movement in all its parts, and with increased power as the bale is compressed more and more; and

It consists in the construction and combination of various parts, as hereinafter more fully described.

A is the frame of the press; B is the box or chamber, in which the material to be pressed is placed; and C is the cover; which said parts are constructed and arranged in the ordinary manner.

D is the follower, which is placed in the lower part of the box or chamber B, and to the cross-bars or frame of which are pivoted the inner ends of the levers E, which pass in through slots in the sides of the box B, and by means of which power is applied to said follower D.

The inner ends of the levers E are enlarged and rounded off, as shown in the figure, and are connected to each other by the chain or chains and bar F, one end of each of which is attached to the upper side of the end of one of said levers, and to the lower side of the end of the other lever, as shown in the figure, so that it will be impossible for one of the said levers to move without moving the other lever at the same time and in the same direction.

By this means, should the power be applied unequally to the two levers, or should all the power be applied to one of said levers, they will both move together, and will carry the follower D up horizontally, pressing the material equally and evenly.

The outer parts of the levers E are connected with the upper part of the frame A by the bar or bars and chains G, the upper ends of which are pivoted to the upper parts of the frame A, and the lower parts of which are branched, the ends of said branched parts being connected with the outer parts of the said levers, as shown in the figure.

In case the connections G are made in the form of bars, they should be jointed at or near their branching

point, as shown in the figure, so as to better and more firmly support and steady the said levers while being acted upon by the power.

H is the rope, one end of which is securely attached to the frame A of the press, and the other end of which is connected with the capstan or other power by which the press is operated.

The rope H, from its point of attachment, passes beneath the roller or pulley I, pivoted to the follower D, below the pivoting points of the levers E, beneath the roller or pulley J, pivoted to the under side of one of the levers E, near its middle part, around the roller or pulley K, pivoted to the lower side of the said lever, near its outer end, thence back beneath the rollers or pulleys J I, beneath the roller or pulley J, pivoted to the middle part of the under side of the other lever E, around the pulley K, pivoted to the under side of the said other lever E, near its end, back beneath the pulleys J and I, and thence to the capstan or other power.

By this arrangement of the rope and pulleys, the first effect of the application of power is to raise the follower D by the upward pressure of the rope H upon the roller or pulley I, and then upon the pulleys or rollers J, the jointed flexible bars or chains G at the same time allowing the outer ends of the levers E to be drawn slightly downward by the action of the said rope H upon the pulleys or rollers K, until the inner ends of the said levers E have been raised first to and then above the level of the outer ends of the said levers E.

Then, as the application of the power is continued, the outer ends of the levers E are drawn inward, the pulleys or rollers I and J being raised from the said rope H, raising the follower D with a force, increasing more and more as the levers E approach nearer to a vertical position, until the material has been compressed to a bale of the desired dimensions.

I claim as new, and desire to secure by Letters Patent—

1. The arrangement of the chains and bars F, with reference to the inner ends of the pointed levers E, as herein described, for the purpose specified.

2. The arrangement of the jointed or flexible connecting-bars or chains G and levers E, with reference to each other and the frame A, as herein described, for the purpose specified.

The above specification of my invention, signed by me, this 30th day of December, 1868.

LEVI DEDERICK.
